WINDOW FRAME CONSTRUCTION

Noie Hirsche, Aberdeen, S. Dak.

Application April 17, 1939, Serial No. 268,221

5 Claims. (Cl. 20—11)

This invention relates to building constructions and more particularly to the sealing of frame work defining openings in the walls of buildings such as window frames.

5 In many building structures and particularly in residences, windows and their frames are so constructed that they are rather effectively sealed against the entrance of air or moisture through the use of weather stripping between the sash and the frame. However, in many types of construction there is improper sealing of the window jambs or frame elements relative to the wall structure so that there is a good chance for moisture and more particularly wind to enter the wall opening at that point.

10 One of the objects of the invention, therefore, is to provide a window frame construction in which effective means is provided for sealing the joint between the frame and the main wall structure.

15 A more specific object of the invention is to provide a window frame structure in combination with a wall structure wherein the usual building paper which covers the sheathing is in effect so arranged that its edge is embedded in or located in the window jamb and wherein the paper extends from the jamb across the joint between said jamb and wall.

20 Another object of the invention is the provision 30 of a window frame structure wherein the parts thereof are effectively yet simply arranged to provide a tightly sealed frame construction and wherein the trim or outer casing can be conveniently applied and wherein said casing conveniently seals the sealed joint formed behind it.

25 These and other objects of the invention will more fully appear from the following description made in connection with the accompanying drawing, wherein like reference characters refer 35 to the same parts throughout the views, and, in which:

Fig. 1 is a fragmentary horizontal section through one side of a window frame and a portion of the upper window sash; and

40 Fig. 2 is a similar view showing a modified form of inner trim and finish.

45 In Fig. 1 there is illustrated a window jamb 3 which extends vertically at one side of the window opening in the wall, and said jamb is 50 suitably secured in abutment with sheathing 4 which is customarily nailed to vertically disposed studding one element of which is shown at 5. The jamb 3 has a window guide strip 6 intermediate its ends which is positioned in a rabbed portion in the outer side face of said jamb.

An inner window guide strip 7 is provided and the lower sash 8 is adapted to slide vertically between these two guides. The corner or junction provided by the outer side and the outer edge face of the jamb is rabbeted as shown in 5 the drawing and receives a strip of wood or other suitable material which constitutes a blind stop 9 and also serves as a guide for the upper sash 10 which slides between said blind stop and the intermediate window guide strip 6. 10

The diagonally opposite corner of the jamb 3 is rabbeted as at 11 to receive the vertical edge portion of a base material such as a sheet of composition board 12 and metal lathing 13 may be placed over the composition board with a 15 layer of plaster 14 applied to the lathing. The corner of the plastered portion may be provided with a bullnose strip 15.

The outer sheathing 4 in the wall structure is 20 customarily overlaid with a layer of building paper 16 and any suitable outer covering or veneer may be placed thereover. In the drawing I have shown the outer finish as comprising metal lathing 17 to which is applied a layer of 25 stucco 18.

25 The vertical edge of the building paper 16 or other suitable fabric extends across the joint between the jamb 3 and the abutting sheathing 4 and across the outer edge face of the sheathing with the extreme edge portion of the building paper 16 turned into the rabbeted corner of the jamb which receives the blind stop 9. After the paper is thus turned into the rabbet, the blind stop is also placed therein and it may be secured by driving a nail through the blind stop 30 and through the edge of the building paper into the jamb. An outer casing or trim strip element 19 may be placed over the building paper and preferably the outer casing material overlies the 35 point where the building paper 16 enters the rabbeted portion of the jamb 3 between said jamb and the blind stop. If desired, instead of running a nail through the blind stop and building paper and thence into the jamb, a nail may be driven through the casing element or outer trim 40 strip 19 through the blind stop 9 and thence into the jamb. The construction is extremely simple 45 yet an absolutely tight joint is produced so that it is impossible for any wind or rain to get in between the jamb 3 and the sheathing 4.

50 In Fig. 2 the jamb 3 is formed in much the same manner as in Fig. 1 except that it extends inwardly to a greater extent to a point flush with the plaster layer 14. Similarly there are provided a blind stop 9 and an intermediate 55

window guide 6. The building paper 16 forms part of a sealed joint and the trim or outer casing element 19 is also as shown in Fig. 1.

The inner window guide 20 will be seen to extend inwardly a considerable distance more than the inner window guide strip 7 in Fig. 1. The composition board 12 is located the same as in Fig. 1 as is the metal lathing 13. The plaster 14, however, extends over to and abuts the projecting portion of the window guide 20. Instead of bullnosing the corner of the plaster in this embodiment, I provide an inner trim strip or casing element 21 which overlies the edge of the plaster and forms a slight lap in conjunction with the extended inner edge of the inner window guide 20.

From the foregoing description, it will be seen that I have provided a relatively simple window frame structure wherein the vertical edge of the building paper is firmly anchored in a vertical rabbeted portion of the window jamb and is retained in said rabbeted portion by a blind stop, and I also provide an outer casing or trim element which covers the point where the edge of the building paper extends into the rabbeted portion of the jamb. It is absolutely impossible for any wind to enter the building between the window jamb and the sheathing 4. Therefore, if the sash is properly weather stripped the resulting structure is such that no wind is admitted into the building as a result of construction in or adjacent the window wall opening and there is consequently material saving in heat. The window jamb itself is of simple structure and the diagonally opposite rabbeted corners thereof provide for easily assembled and extremely tight joints on both the inner and outer faces of the wall where they meet the window jambs.

It will, of course, be understood that various changes may be made in the form, details, ar-

rangement and proportions of the various parts without departing from the scope of my invention.

What is claimed is:

1. In a building construction, a pair of spaced vertical window jamb elements having vertical rabbeted portions, blind stops positioned within said rabbeted portions in their opposed side faces and sheets of building material extending along edge faces of said jambs having vertical edge portions extending into the rabbeted portions of said jambs between said jambs and said blind stops, at an angle to said edge faces. 5

2. In a building construction, a pair of spaced vertical window jamb elements having vertically disposed rabbeted portions, blind stops positioned in said rabbeted portions, sheathing material abutting said jambs, and sheets of building fabric overlying said sheathing and having vertical edge portions inserted in said rabbeted portions of 15 said jambs between the jambs and said blind stops.

3. The structure in claim 2 and trim strips positioned against said building fabric and overlying the place of entry of said building fabric 25 into said rabbeted portion.

4. In a building construction, a pair of spaced jamb elements having interior and exterior side faces and interior and exterior edge faces, said jambs having rabbeted portions at the junction 30 of their exterior edge faces and side faces, blind stops positioned within said rabbeted portions, and building fabric having edge portions terminating in said rabbeted portions between said jambs and said blind stops. 35

5. The structure in claim 4 and trim strips positioned against said building fabric and overlying the points where said building fabric enters said rabbeted portions.
